UNITED STATES PATENT OFFICE.

ROBERT W. LYLE, OF SOUTH RIVER, NEW JERSEY, ASSIGNOR TO WILLIAM JAMES LYLE,
OF SOUTH RIVER, NEW JERSEY.

BUILDING CONSTRUCTION AND BLOCK THEREFOR.

1,265,220.

Specification of Letters Patent.

Patented May 7, 1918.

Application filed October 4, 1912, Serial No. 723,870. Renewed February 21, 1918. Serial No. 218,590.

To all whom it may concern:

Be it known that I, ROBERT W. LYLE, a citizen of the United States, and resident of South River, in the county of Middlesex 5 and State of New Jersey, have invented certain new and useful Improvements in Building Constructions and Blocks Therefor, of which the following is a specification.

This invention relates to building constructions and blocks therefor, and it has for its object to provide an improved building construction and a block therefor which will afford maximum strength in the wall structure under all conditions of use and in 15 which the block will be adapted for convenient and inexpensive manufacture and will possess the advantages of simplicity in construction as well as strength in resistance to strains. 20 A further object of my present invention and improvements is to provide an improved building block which will be especially adapted for affording an effective closure at the mortar beds against the possibility of 25 the passage of moisture through the wall joints by capillary or other action, and which will provide in a simple and economical manner interlocking means between the blocks when assembled in a wall structure. 30 The main subject matter of my present invention has particular relation to the type of two-step hollow building blocks such as shown in the patent to Denison, No. 942,621, dated December 7, 1909, in which 35 the block is constituted by a main portion and a supplementary portion projecting therefrom at one side and forming a step at the top and bottom surfaces of the blocks, said blocks being superposed in reversed position in wall construction.

In the drawings—

Figure 1 is a perspective view of a building block embodying my improvements.

Fig. 2 is an end view of one type of wall construction as built with these improved blocks.

Fig. 3 is a vertical sectional view, taken on the line $\alpha-\alpha$, of the wall construction as shown in Fig. 2.

50 Corresponding parts in all the figures are denoted by the same reference characters.

Referring to the drawings, 1 designates the block, which is constructed integrally of clay or other suitable material and is of 55 the usual hollow construction, formed by

longitudinal bores which produce an outer shell and inner webs or walls. In the general construction of the improved block, as herein shown, it is constituted by a main portion from one side of which projects a 60 supplementary portion of less vertical extent than the main portion and producing a longitudinal step at the top and bottom surfaces of the block, whereby the block is in its main external contour of step form. The 65 relative dimensions of the step portions, as well as the general dimensions of the block itself, may be as desired.

It will be understood that hollow building blocks of the character to which my improvements relate are designed to be formed 70 in continuous lengths in an ordinary clay die-press and then cut into the desired length of individual block and conveniently burned in the kiln. My improvements are 75 therefore adapted to produce, under these conditions of manufacture, a block which can be more readily and economically formed in a die-press and which will be extremely simple and of light character with 80 reference to the quantity of clay used without sacrificing the maximum conditions of strength and resistance to strains as required in wall construction.

In the Denison type of two-step block, 85 hereinbefore referred to, the block comprises a hollow rectangular head and a hollow tongue extending from the middle of the side of the head and of a thickness substantially half the thickness of the head, 90 the side of the head adjacent to the tongue forming one continuous alined wall across the end of the tongue, and the tongue being provided with an internal web parallel to and adjacent to said side of the head. In 95 such construction, the location of the web in the tongue is such that the web will take a position substantially in vertical alinement with the side wall of the head which extends across the end of the tongue, when such 100 blocks are superposed in reversed position substantially in the manner as shown in Fig. 2 of the accompanying drawings, and there is thus produced two vertical tiers of internal webs in the line of vertical strain 105 and at each side the steps which are formed by the overlapping shoulders provided by the heads and tongues. In this construction of block, the relative conditions of a rectangular head, and the tongue extending from 110

the middle of the head and of a thickness substantially half the thickness of the head, render necessary the extra internal web within the tongue, as otherwise no vertical tier of internal strain-resisting walls would extend in a continuous series when the blocks are superposed in reversed position in wall construction. The type of construction as just indicated is open to disadvantages, and limitations in adaptability to use, and the essential provision of the internal web within the tongue and adjacent to the side of the head which extends across the tongue produces a relatively thickened condition at the middle of the block which renders it difficult to effectively run the material in continuous lengths through an ordinary clay die-press and precludes facility and economy in manufacture.

20 The conditions and disadvantages as just above stated are obviated by my improvements, as hereinafter described, which provide an improved block of the two-step type which can not only be produced with facility 25 and economy in manufacture but in which the conditions of non-uniform or excess thickness at any point will be obviated, and which will still afford a continuous vertical tier of internal strain-resisting walls when 30 the blocks are superposed in reversed position, and will otherwise meet all the required conditions of use. My improvements furthermore provide a block which has a uniform condition of external shell 35 walls, and corresponding uniform conditions of internal webs or walls only at the lines of division between the longitudinal bores of the main portion or head and of the supplementary side portion or tongue, 40 and there is also no essential limitation to the thickness of the side portion or tongue with relation to the main portion or head, nor to the location of said side portion with respect to the middle of the side of the head, 45 as the side portion in my improved construction can be of any suitable thickness affording the step conditions at the top and bottom surfaces of the block and can be located at a desired position with relation to 50 the side of the head.

In carrying out my improvements, the integral body of the block 1 comprises a main portion or head, 2, which forms one side of the block, and a narrower supplementary portion or tongue, 3, projecting at the inner side of said main portion and forming the opposite side of the block, said narrower portion 3 being of course less in its vertical extent than the vertical extent 55 of the main portion 2, whereby the continuous shoulders forming the longitudinal steps, as at 4 and 5, respectively at the horizontal top and bottom surfaces of the block, are produced. Preferably, the main 60 or body portions of the respective step por-

tions 2 and 3 approximately correspond in sidewise width, though they may be varied in relative sidewise width under some conditions of use, and the bores which form the hollow body of the block extend longitudinally in the respective step portions. The hollow construction is preferably produced by a series of two or more longitudinal bores, as at 6, extending centrally in the main step portion 2, and similar or corresponding bores, as at 7, extending centrally in the supplementary step portion 3, said bores 6 and 7 being divided by horizontal longitudinal webs or partitions, as at 8, and the bores of the respective portions 2 and 3 80 being divided by a vertical web or partition, as at 9, extending centrally of the block between the respective step portions. The hollow construction is thus such that the internal bores form a body shell constituted 85 by external surrounding walls and internal webs or partitions, one of which latter, as at 9, extends vertically and centrally of the block between the hollow step portions 2 and 3.

In the improved block, as constructed according to my invention, a vertical tier of strain-resisting body walls internally of the construction and extending throughout the superposed tiers or courses of the blocks 95 when the latter are arranged in reversed position in walls, as for instance the wall construction shown in Figs. 2 and 3, is produced by having the heads or step-extensions of the hollow main portion 2 of variable size at the respective top and bottom stepped surfaces of the block, the construction being such that the head or step-extension, as shown at 10, of the main portion 2 at one horizontal surface of the block, is 100 narrower in sidewise width than the head or step-extension, as shown at 11, at the opposite end of the main portion 2 and at the opposite horizontal surface of the block.

The preferred construction for carrying 110 out the variable-head feature just stated has the inner shell wall, 12, of the narrow step-extension 10 at a vertical plane intersecting the bore 6 of the hollow body portion of said main portion 2, and the outer face of 115 said wall 12 is approximately on the plane of the inner face of the vertical internal web or wall 9 which divides the main hollow portion 2 from the supplementary hollow portion or tongue 3. Thus, at the horizontal surface of the block which has the relatively narrow head or step-extension 10, the horizontal step surface of the supplementary portion or tongue 3, which surface is formed by the external shell wall of said 120 portion 3, as indicated at 14, is wider on the horizontal plane than the narrow head or step-extension 10 and extends over the internal vertical dividing web or wall 9. At 125 the opposite horizontal surface of the block, 130

the head or step-extension 11 has its inner wall, 15, formed by a continuation of the central dividing web or partition 9 and is on the vertical plane thereof, so that said 5 step-extension 11 is wider on the horizontal plane than the narrow step-extension 10 at the other horizontal surface of the block and the step surface of the supplementary portion or tongue 3, which is formed by its 10 external shell wall, as indicated at 16, extends only to the plane of said central dividing web or partition 9 and is thus narrower than its supplementary surface which is formed by the shell wall 14 at the opposite 15 horizontal surface of the block.

Under the relative conditions of step construction as just described, the integral body of the block, comprising the hollow main portion 2 and the hollow supplementary portion or tongue 3, has at one horizontal surface two steps which are of a determined size or width on the horizontal plane of the block, and at the other horizontal surface two steps of variable size with relation to 20 said first mentioned steps, one of said variable size steps being narrower in its sidewise width than its complementary step at the opposite horizontal surface of the block and the other of said variable size steps being 25 wider in its sidewise width than its complementary step at the opposite horizontal surface of the block.

This improved construction produces, when the blocks are superposed in reversed 30 position in wall construction, as shown in Fig. 2, a composite structure in which the internal central dividing web or partition 9 between the respective main and supplementary portions of the block will be in the 35 same vertical plane with the internal central dividing web or partition 9 of the next superposed block, and thus provide in wall construction a continuous vertical tier of internal strain-resisting body walls extending 40 centrally between the main and supplementary portions 2 and 3 of the blocks and throughout the superposed tiers or courses 45 of the blocks. It will be noted that the outer walls, 17 and 18, respectively, of the main 50 hollow portion 2 and the supplementary hollow portion or tongue 3 will also be in the same vertical plane and produce corresponding 55 continuous vertical tiers of strain-resisting body walls at the opposite vertical faces of the superposed tiers or courses of the blocks. This construction effectively meets 60 downward strain and produces a wall structure which, while it is of hollow character, possesses great strength and resistance in the 65 vertical plane and does not require a thickening of the central portion of the two-step block by the interposition of a supplementary web in the hollow body of the side portion or tongue 3.

At the horizontal joints, in walls con-

structed with this type of building block, the horizontal mortar courses, as at 19, are laid between the respective stepped surfaces of the superposed blocks, and the passage of moisture at these horizontal joints is resisted by the direct break in the plane of the joint which is formed by the vertical faces of the step shoulders between the block portions 2 and 3. 70

My present invention furthermore comprises improved means for more effectively resisting the passage of moisture at the horizontal joints between the blocks, and for also providing an effective interlocking construction between hollow building blocks at intervening joints. In carrying out this feature of my improvements, the external shell walls of the hollow block, which are designed to abut at intervening joints between the blocks, are bowed to produce projections, 75 as at 20, and recesses, as at 21, extending longitudinally of said walls at the abutting surfaces of the blocks, whereby an interlocking tongue and groove construction is provided at the joints between 80 abutting blocks. The bowed portion of the external shell walls of the hollow block provides a simple and effective means for forming an interlocking construction between such blocks without increasing the thickness of the external wall and without varying its uniform conditions, and this improved interlocking construction therefore 85 does not impair the conditions of rapid and economical manufacture of the blocks in continuous lengths in an ordinary clay die-press. The bowed portion of the external walls may 90 be in its cross sectional contour in the form of a curve or direct angle or other shape whereby the wall is deflected from its 95 straight plane.

The preferred construction, in the application of this bowed-wall feature of my invention to the two-step block as herein shown, comprises an outwardly-bowed portion 100 20 at one of the horizontal surfaces of each of the hollow step portions 2 and 3, thus forming projections or tongues at that surface of the block, and an inwardly-bowed portion 21 at the opposite surfaces of said 105 portions 2 and 3, which form grooves or recesses at that surface of the block, but it will be understood that such tongue and groove construction may be provided upon only one of the step portions 2 or 3 and that, 110 within the scope of this feature of my improvements, such bowed construction of the external walls of the hollow block may be provided to form tongue-projections or 115 groove-recesses as desired and at any suitable points upon the abutting surfaces of adjoining hollow blocks to afford an interlocking construction at such joints.

The advantages of my improvements will 120 be readily understood by those skilled in the 125 130

art to which they appertain. The improved variable head or step-extension construction as hereinbefore described, in the two-step type of block herein shown, produces a continuous vertical central tier of strain-resisting body walls extending throughout the superposed courses of the reversed blocks in wall construction without the employment of any supplementary or additional 10 internal webs or walls other than the single dividing web or partition between the two hollow step portions 2 and 3, and the improved block is therefore extremely simple in construction and has a uniform thickness 15 of external shell walls and internal dividing webs or partitions between the bores without excess thickness at any portion of the integral body, whereby the block in its entirety is adapted for rapid and economical 20 manufacture. The feature providing interlocking conditions at abutting surfaces of the blocks by bowing or deflecting the external shell walls also avoids any excess thickness at such interlocking point and maintains 25 the uniform conditions of the wall structure extending throughout the hollow body, and this bowed or deflected wall, producing tongue-projections or groove-recesses, is adapted to a wide range of effective employment as interlocking means and a direct 30 break in the joints between the blocks.

It will be understood that, under some circumstances of construction within the scope of my present improvements, the improved 35 variable-head block embodying the features herein described may be constructed with a plurality of steps in excess of the two-step type herein shown; for instance, with three steps according to the construction shown 40 in my co-pending application Serial No. 723,869.

I do not desire to be understood as limiting myself to the detail construction and arrangement of parts as herein shown and 45 described, as it is manifest that variations and modifications therein may be resorted to, in the adaptation of my invention to varying conditions of use, without departing from the spirit and scope of my invention 50 and improvements. I therefore reserve the right to all such variations and modifications as properly fall within the scope of my invention and terms of the following claims.

Having thus described my invention, I claim and desire to secure by Letters Patent:

1. An improved building block, comprising an integral body having successive steps 60 at its horizontal top and bottom surfaces and having horizontal longitudinal bores

forming a hollow construction and producing a vertical internal dividing web or wall between the respective step portions, said body having a step head or step-extension 65 at one of its horizontal surfaces of less width than the complementary step head or step-extension at the opposite horizontal surface, whereby when said blocks are superposed in reversed position in wall construction 70 a continuous vertical tier of strain-resisting body walls will be formed throughout the superposed tiers or courses of the blocks.

2. An improved building block comprising an integral body having successive steps at its horizontal top and bottom surfaces and having horizontal longitudinal bores forming a hollow construction and producing a vertical internal dividing web or wall 80 between the respective step portions, said body having a step head or step-extension at one of its horizontal surfaces of less width than the complementary step head or step-extension at the opposite horizontal surface, the relative construction and arrangement being such that the vertical step wall of said relatively narrow step head or step-extension is within the vertical plane of the inner face of the vertical internal web or 85 wall which divides the respective step portions, whereby the internal webs or walls which divide the respective step portions will be in alinement and conjointly form a continuous vertical tier of strain-resisting 90 body walls when said variable-head blocks are superposed in reversed position in wall construction.

3. In building construction, a wall structure comprising building blocks having an 100 integral hollow body with internal vertical webs or walls and provided with successive steps at their horizontal top and bottom surfaces, said blocks being superposed in reversed position in horizontal courses, the 105 step heads or step-extension at the respective top and bottom surfaces of the step portions of said blocks being of variable width, whereby said reversed and superposed blocks have relatively uniform abutting step surfaces at the horizontal joints of said wall and a continuous vertical tier of strain-resisting body walls are formed by said internal vertical webs or walls throughout the wall structure.

In testimony whereof I have signed my name in the presence of the subscribing witnesses.

ROBERT W. LYLE.
